UNITED STATES PATENT OFFICE.

ANTHONY C. CARAMORE, OF JAMAICA, NEW YORK.

SWIMMER'S EMERGENCY AID.

Application filed April 25, 1923. Serial No. 634,448.

To all whom it may concern:

Be it known that ANTHONY C. CARAMORE, a citizen of the United States, residing at Jamaica, in the county of Queens and State 5 of New York, has invented certain new and useful Improvements in Swimmers' Emergency Aid, of which the following is a specification.

This invention has reference to an emergency aid for swimmers, and is designed to support a disabled swimmer in the water until he has sufficiently recovered, or the support will sustain him in the water until help reaches him.

15 In accordance with the invention, the device comprises a container having a strap capable of being fastened around the waist of a swimmer in a manner to offer no resistance or impedance to the swimmer's 20 movements.

The arrangement is such that when an emergency occurs to a person in the water, such as cramp or exhaustion, or any other accident that may happen to the swimmer 25 that will result in disabling him, he is able to seize a ring at the end of a ripper tape, and by a firm downward pull rips or severs a water-proof covering from a chemical container, so that water gains access to the 30 chemical in the container to immediately generate gas which inflates a buoyant gas holding chamber to keep the swimmer afloat until help reaches him, or until he can reach land.

35 The invention will be best understood from a consideration of the following detailed description, taken in connection with the accompanying drawings forming part of this specification with the understanding, 40 however, that the invention is not confined to any strict conformity with the showing in the drawings, but may be changed and modified, so long as such changes and modifications mark no material departure 45 from the salient features of the invention as expressed in the appended claim.

In the drawings:

Figure 1—is a face view of the emergency aid structure.

50 Figure 2—is a side elevation thereof.

Figure 3—is a detailed view of the chemical container, and

Figure 4—is a longitudinal vertical section through the device, Figure 3.

55 Referring to the drawings, there is shown a buoyance chamber 1, which may be con-

structed of cotton fabric or other appropriate material with an expanded upper end 2, and a lower central dependent extension 3, the part 3 being of narrowed configuration 60 simulating a tail extension. Within the upper widened portion 2, and extending into the tail continuation 3 is an appropriate container 4, designed to enclose an amount of material, such, for instance, as 65 calcium carbide, which when subjected to the action of water will generate a large volume of gas, the container 4 being lodged on the lateral expansion 2, and extending down into the tail extension 3. 70

At the upper end of the container 4 is an eye 9, constituting a finger hold for sustaining the device, the weight of the chemical contents of the container 4 being insufficient to disturb frictional engagement 75 of the container within the body 1 of the structure.

Surrounding the container 4, and under riding said container is a band or web 7, having its terminals joined together beneath the container 1. The container 4 is perforated at numerous places as indicated at 8, to admit water to the interior of the container, unless provision be made for contrary action, which may be brought about 85 by rendering the covering for the container temporarily water-proof by a coating of paraffin or some other suitable material.

When the device is in operative condition, the casing 5 is so arranged as to shield the 90 contents of the chemical container 4 from access of water, until it be desired that such condition should be established, at which time, a pull on the band 7 will rip the casing 5, so that water may find ready access 95 to the contents of the container 4, through the perforations 8 whereupon the water will immediately reach the contents of the casing 4 and generate acetylene gas or some other gas by the chemical reaction caused by 100 the access of water thereto.

The portion 2 of the structure is made quite large so as to exert such buoyancy when the device is submerged in water, as to readily sustain the human body in such position that the head is well above the surface of the water, so that the body cannot sink even though the person supplied with the device is disabled. In order to sustain the container 4, the eye 9 is connected by 105 an additional strap 10 to the main portion 2 of the structure, and the band 7 is con-

tinued below the tail portion 3, and is connected to a ring 11, thus permitting the wearer of the device to exert a pulling force upon the band 7 to surely rupture or pull 5 apart the band 7, and thus expose the perforations 8 to access of water and permit the generation of gas which will immediately find its way into the lateral expansion 2 of the container 1, at a high point in the device 10 to exert a buoyant tendency and thus sustain the head of the disabled person well above the water level to assist the person in reaching a point of safety or sustain the person for as long a time, as may be necessary to permit a rescue. 15

The operation of the device when in use is wholly automatic, requiring only the ripping of the band 7 from connection with the structure to admit the access of water

to the gas generating chemical within said 20 container.

What I claim as new, and desire to secure by Letters-Patent, is:

In a device of the class described, a container having an expanded upper end to 25 house gas, a receptacle for a gas producing chemical responsive to the action of water, said receptacle having perforations, a ripping band for exposing the interior of the receptacle to the action of water and excluding the water therefrom until the band is ruptured, and means attached to the ripping band operable for rupturing the same 30 to permit access of water to the contents of the container. 35

In testimony whereof I affix my signature:

ANTHONY C. CARAMORE.
